UNITED STATES PATENT OFFICE.

ANDREW WEBSTER, JR., OF NEW YORK, N. Y., ASSIGNOR TO CHARLES M. BAILEY, OF SAME PLACE.

DESIGN FOR CARPET.

Specification forming part of Design No. 6,335, dated December 31, 1872.

To all whom it may concern:

Be it known that I, A. WEBSTER, Jr., of the city, county, and State of New York, have invented a new and original Design for a Carpet, of which the following is a specification:

The accompanying photograph fully illustrates my new design.

This invention relates to a new design for carpets and other fabrics of entirely novel and original conception. Its central ornament is composed of an elongated rectangle, whose ends are carried out to form central pointed projections and steps, as shown, while a semicircular projection is formed on the middle of each side of said rectangle. These semicircular projections enter partly into and keep from view portions of smaller squares that are

arranged at the sides of the rectangles. A sort of zigzag border embraces this rectangular figure and its adjoining smaller squares, and has branches formed in it, as shown, producing thus a peculiar effect. The border is ornamented by short lines or elongated spots. The larger figure contains a cross-shaped center ornament, around which decorating scrolls are arranged. Checker-board centers are formed within the smaller squares.

I claim as my invention—

The design for a carpet, as shown.

A. WEBSTER, Jr.
